UNITED STATES PATENT OFFICE.

EMIL EBERHART, OF EDWARDSVILLE, ILLINOIS.

REMOVABLE SANITARY COVER FOR FREEZER CANS.

Application filed December 2, 1925 Serial No. 72,825.

This invention relates to new and useful improvements in removable sanitary covers for freezer cans now commonly placed in display counters used in meat markets and other places where perishable articles are kept for sale.

It is now the usual practice to place a freezer can at each end of the display counter to keep the air which is in circulation at the proper temperature. The front of the can is usually exposed and presents an unsightly appearance and it is the purpose of my invention to overcome this objection by covering the front of the can and the ice contained therein with a suitable sanitary cover that will not interfere with the proper circulation of the cooled air.

In the accompanying drawings, which are for illustrative purposes only and are therefore not drawn to scale:

Figure 1 is an end view of the cover in position, showing the refrigerator in dotted lines.

Figure 2 is an enlarged detail front view of the removable cover.

Figure 3 is a back view of the cover and Figure 4 is an edge view.

Referring to the drawings for a more particular description of my invention and in which drawings like parts are designated by like reference characters throughout the several views, A indicates the display counter, B the freezer cans placed in opposite ends of the counter and C the removable covers for the freezer cans.

The removable cover consists of a piece 1 of sheet iron or other suitable metal formed with a plurality of transverse openings 2 corresponding in size and number to the usual pipes or openings extending through the freezer can. The openings 2 are covered by elongated strips 3 of wire netting or other suitable reticulated material which are soldered or otherwise permanently secured, as at 4, to the back of the cover. The cover is formed at one edge with an inturned flange 4

which hooks over one edge of the freezer can and whereby the cover is held in removable position. The front of the cover is preferably covered with white enamel to match the 50 inside of the counter.

When my cover is mounted in place on the freezer can, it covers up the ends of the air pipes or openings and the ice in the can, which would ordinarily present a very unattractive 55 appearance, while at the same time the free circulation of the ice cooled air through the air pipes and counter is not interfered with to any appreciable extent.

From the foregoing description taken in connection with the drawings, it is thought that the construction, operation and advantages of my invention will be readily understood without requiring a more extended explanation.

Having described my invention, what I claim as new and desire to secure by Letters Patent, is:

1. A sanitary cover for a refrigeration unit having air circulating pipes passing therethrough consisting of a piece of sheet iron or other suitable metal formed with a plurality of transverse openings corresponding in size and number to the air pipes of the refrigeration unit and strips of wire mesh fastened to 70 the back of the cover and covering said openings.

2. A sanitary cover for a refrigeration unit having air circulation pipes passing therethrough consisting of a piece of sheet iron 80 or other suitable metal formed with a plurality of transverse openings corresponding in size and number to the air pipes of the refrigeration unit and strips of wire mesh fastened to the back of the cover and covering 85 said openings, and an inturned flange formed at one edge of the cover by which the cover is hung on the unit.

In testimony whereof he affixes his signature,

EMIL EBERHART.
